UNITED STATES PATENT OFFICE.

LOUIS B. HARVEY, OF STOCKTON, CALIFORNIA, ASSIGNOR TO HARVEY RIM & WHEEL COMPANY, INC., OF BUFFALO, NEW YORK.

FIXED-RIM CONSTRUCTION FOR DISK WHEELS.

Application filed March 16, 1920, Serial No. 366,215. Renewed May 9, 1921. Serial No. 468,048.

To all whom it may concern:

Be it known that I, LOUIS B. HARVEY, a citizen of the United States, residing at Stockton, in the county of San Joaquin, 5 State of California, have invented certain new and useful Improvements in Fixed-Rim Constructions for Disk Wheels; and I do declare the following to be a full, clear, and exact description of the same, reference being had to the accompanying drawings, and to the characters of reference marked thereon, which form a part of this application.

This invention relates to improvements 15 in fixed rim structures for wheels, especially disk wheels; and of a type adapted to be used in connection with a demountable rim of the type shown in my co-pending application for sectional rim, Serial No. 284,983, 20 filed March 25th, 1919.

This fixed rim structure itself is the same as is shown in my co-pending application for patent on disk wheels Serial No. 282,935, filed March 15th, 1919.

25 The principal object of the present invention is to provide a reinforced hollow box like structure which will be light and strong, and to which the disks of the wheel may be secured in a removable manner 30 while holding the same against radial movement relative thereto, and provided with a locking ring for holding the demountable rim in place which is clamped to the fixed rim by the same means which 35 hold the disks thereto.

A further object of the invention is to produce a simple and inexpensive device, and yet one which will be exceedingly effective for the purposes for which it is designed.

40 These objects I accomplish by means of such structure and relative arrangement of parts as will fully appear by a perusal of the following specification and claims.

The figure on the drawings is a cross section 45 through the fixed rim.

Referring now more particularly to the characters of reference on the drawings, the numeral 1 denotes the inner ring of the fixed rim, having an annular flange 2 on its inner 50 edge projecting outwardly therefrom and terminating in a flared portion 3.

Spaced outward from the ring 1 is a ring 4 having a horizontally disposed V-shaped holding flange 5 on the inner edge, one side 55 of which seats against the flare 3, and is

welded thereto as at A. An annular flange 6 projects inwardly from the outer edge of the member 4, and overlaps the outer edge of the ring 1, to which it is welded as at B.

The holding flange 5 is adapted to receive 60 an angled annular flange 7 on the demountable rim 8, which is of that type shown in my previously mentioned co-pending application on sectional rims.

An inner disk 9 is arranged to extend from 65 the hub of the wheel to the flange 2, having its outer termination abutting against the flare 3.

An outer disk 10 and an intermediate reinforcing disk 11 terminate at the top of the 70 ring 4 and rest against the flange 6 of such ring, the arrangement and shape of these disks being as shown in my copending disk wheel application hereinbefore mentioned.

These latter disks are held in place against 75 the flange 6 by means of a locking ring 12, which has a V-shaped flange 13 opposite to the flange 3 and in the same horizontal plane and adapted to receive and hold an angled flange 14 on the rim 4 opposite to the flange 7 80 thereon.

The disks, fixed rim and locking ring are all clamped together by means of common bolts 15 having nuts 16 on the outer ends thereof seating against washers 17 between 85 the same and the ring 12.

The flange 6 and ring 12, and the disks 10 and 11 at that point, are curved convexly as at C, in order that an interlocking effect will 90 be had between these members.

From the foregoing description it will be readily seen that I have produced such a device as substantially fulfills the object of the invention as set forth herein.

While this specification sets forth in detail the present and preferred construction of the device still in practice such deviations from such detail may be resorted to as do not form a departure from the spirit 95 of the invention, as defined by the appended 100 claims.

Having thus described my invention what I claim as new and useful and desire to secure by Letters Patent is:—

1. A built-up fixed rim structure comprising a ring having an outwardly projecting flange on one edge thereof, such flange terminating in an outwardly flared portion, another ring having a shoulder seating on the flared portion of the flange 105 110

and being welded thereto, and having also an inwardly projecting annular flange on the opposite side extending past the first named ring to the inner edge thereof and 5 being welded thereto, and a removable rim-locking ring positioned on the outside of the last named flange and adapted to be held thereagainst.

2. A fixed rim structure for disk wheels 10 comprising a hollow rigid member having an outwardly projecting flange on its inner side adapted to receive one side of a demountable rim thereagainst, a locking ring on the outer side of the hollow member and 15 having a flange thereon in transverse alignment with the first named flange, and adapted to bear against the rim, two of the disks of the wheel terminating between the hollow member and the locking ring and 20 the other terminating adjacent the opposite side of the hollow member, and common bolts through all the disks, the hollow member and the locking ring to bind the same together.
- 25 3. A built-up fixed rim structure for disk wheels comprising a ring having an outwardly projecting annular flange on one edge thereof adapted for connection to a disk of the wheel, such flange terminating 30 in an outwardly flared portion, and another ring having a shoulder seating on the flared portion of the first named flange and being welded thereto and having also an inwardly

projecting annular flange on the opposite side extending past the first named ring to 35 the inner edge thereof and being welded thereto, such flange being adapted for connection to another disk, there being a removable rim-locking ring positioned on the outside of the last named flange and adapted 40 to be held thereagainst, the disk passing therebetween.

4. In a wheel of the character described, a fixed rim comprising inner and outer concentric members, and side walls connecting 45 said members and forming therewith a hollow, boxlike structure.

5. In a wheel of the character described, a fixed rim comprising inner and outer concentric members, each having a side flange 50 forming one of the side walls of the said rim.

6. In a wheel of the character described, a fixed rim comprising inner and outer concentric members, the outer member being provided at one edge with an inwardly extending flange forming one of the side walls of said rim and the inner member being provided at the opposite edge with an outwardly extending flange forming the other side wall 60 of the rim, and means for securing the flange of each rim section to the body of the other section.

In testimony whereof I affix my signature.

LOUIS B. HARVEY.
